Primary Examiner — Ian Simmons*Assistant Examiner* — Carissa C Fitts(74) *Attorney, Agent, or Firm* — DLA Piper LLP US(57) **CLAIM**

I claim the ornamental design for a lantern, as shown and disclosed.

DESCRIPTION

FIG. 1 is a front perspective view of a lantern;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken line showing is for environmental purposes only and forms no part of the claimed design.
